United States Patent Office

Des. 180,771
Patented Aug. 13, 1957

180,771

WASHROOM UNIT FOR RAILWAY CARS

Walter B. Dean, Narberth, Pa., assignor to The Budd Company, Philadelphia, Pa., a corporation of Pennsylvania

Application July 10, 1956, Serial No. 42,193

Term of patent 14 years

(Cl. D66—1)

FIG. 1

FIG. 2

Fig. 1 is a front elevation of a washroom unit for railway cars embodying my new design; and

Fig. 2 is a horizontal section taken on the line 2—2 of Fig. 1.

The top and rear portions, not shown, are conventional.

I claim:

The ornamental design for a washroom unit for railway cars, substantially as shown and described.
